United States Patent Office

Des. 192,458
Patented Mar. 20, 1962

192,458

AIRCRAFT

Edward P. Knauer, Kenmore, Emerson W. Stevens, Snyder, and Mitchell Zurawinski, Niagara Falls, N.Y., assignors to Bell Aircraft Corporation, Wheatfield, N.Y.

Filed Dec. 3, 1957, Ser. No. 48,765

Term of patent 14 years

(Cl. D71—1)

FIG. 1

Des. 192,458

PAGE 2

FIG. 2

FIG. 3

FIG. 4

FIG. 5

FIG. 1 is a top plan view of an aircraft, showing our new design;

FIG. 2 is a side elevational view thereof;

FIG. 3 is a front elevational view thereof;

FIG. 4 is a top perspective view thereof showing the aircraft power plants in one operative position; and

FIG. 5 is a bottom perspective view thereof, showing the aircraft power plants in another operative position.

We claim:

The ornamental design for an aircraft, as shown.
